LATCH AND LOCK MECHANISM

Waldemar A. Endter, Long Beach, Calif.

Application November 8, 1943, Serial No. 509,485

24 Claims. (Cl. 70—150)

This invention relates to latch mechanisms of the rotary bolt type, and is directed principally to improvements in locking means and their controls for maintaining the bolt against reverse or anti-latching rotation from latched positions. Although the invention is applicable to various specific types and forms of latch mechanisms for holding relatively movable members in associated or engaged condition, it is particularly adapted to automobile door type latches and, accordingly, will be described with reference to such mechanisms.

Latch mechanisms of this type comprise a rotary bolt movable bodily into engagement with a keeper, and thereafter rotatable into latched position under the influence of an actuating device, e. g. one or more spring-urged cams having wedge engagement with the bolt to exert against it an advancing thrust, and imposing a holding resistance to reverse or anti-latching rotation of the bolt, until released in the usual manner by operators controllable at the inside and outside of the door. The present invention is concerned with improved bolt locking means for positively securing or dogging the bolt against anti-latching rotation, independently of the bolt actuating or camming means.

One major object of the invention is to employ a manually controllable locking means, preferably in the form of a simple dogging element or assemblage, normally retracted from holding relation to the bolt and movable into the path of anti-latching rotation of the bolt to prevent such rotation, said locking means being characterized by its displaceability to bolt releasing position by advancing rotation of the bolt, as upon its movement against the keeper during engagement of the latch. In conjunction with such locking means, the invention contemplates various features of control, such as the provision of a key controlled operator for locking and releasing the locking means, and an inside handle actuated control operable to similar effect, the lock setting and releasing in either instance preferably being independent of the bolt camming or other actuating means.

Another contemplated combination of controls for the locking means may include, together with the key-controlled operator, an inside handle actuated control operable to retract the bolt actuating means but inoperative to control the locking means, and a second inside (e. g. push button) control independently operable to set and release the locking means.

A further object of the invention is to pro-

vide a bolt take-up means the general purpose and effect of which is to maintain the bolt against loose movements otherwise resulting from permitted reverse rotation, independently of the bolt advancing means. Preferably the take-up means constitutes essentially a part or feature of the bolt locking means, so that in the locked position of the latter, the bolt is held against reverse rotation at any of different positions. Therefore, in its latched condition, and despite retraction of the bolt actuating means, the bolt is securely held so that looseness will not develop within the mechanism itself or in the position of the door.

The stated objects, as well as additional features and objects will be explained and understood to better advantage by reference to the accompanying drawings which illustrate the invention in certain of its typical and preferred forms. In the drawings:

Fig. 1 is an elevational view of the mechanism in latched condition, with the cover plate removed;

Fig. 2 is a section on line 2—2 of Fig. 1 showing the outside and key-controlled operators, and their association with the parts appearing in Fig. 1;

Fig. 3 is a view similar to Fig. 1 showing the locking plate complete in bolt locking position and the holding or camming means and step plate in released position;

Fig. 4 is a section on line 4—4 of Fig. 1;

Figs. 5, 6, 7 and 8 are perspective views of the cam, step plate, releasing plate and locking plate, respectively;

Fig. 9 is a perspective view of the cam, step plate and releasing plate in assembled relation;

Fig. 10 is a view similar to Fig. 1 illustrating a variational form of the invention;

Fig. 11 is a section on line 11—11 of Fig. 10, with an added showing of a push-button connection with the locking plate;

Fig. 12 is a fragmentary view illustrating the position of the lock plate of Fig. 10, in bolt locking position;

Figs. 13 and 14 are front and right side views, respectively, of the cam element in the variational form;

Figs. 15 and 16 are front and right side views, respectively, of the locking plate; and

Figs. 17 and 18 are front and right side views, respectively, of the take-up wedge associated with the locking plate.

Referring first to the form of the invention

shown in Figs. 1 through 9, certain parts of the

mechanism are contained within a case 10 having side flanges 11 and top and bottom flanges 12 and 13 to which is secured the cover plate 14 as by bolts 15 or other suitable means. Formed integrally with the case is a guide 16 at opposite sides of which are positioned the later described bolt actuating means of the retracting plate. The cover plate 14 has an opening at 16 to receive an independently mounted keeper 17, supported for example on a door pillar, and engageable with the rotary bolt 18 by movement of the door-carried case and bolt assembly against and along the keeper, such movement being permitted by reception of the keeper within an opening at 16 in the cover plate 14. The keeper is engageable with a transversely extending member 20 secured to the case flange 13, the keeper in the latched position of the parts being confined between the bolt and the upper surface of member 20. The rotary bolt 18 may be of the conventional type, comprising a suitable number of radially extending, equi-angularly spaced heads 18a, rotatable from a position of initial engagement with the end 17a of the keeper to the latched position appearing in Fig. 1. The bolt is rotatable on a shaft 21 secured at 22 to the cover plate 14 and supported at 23 within the case 10.

The rotary bolt is urged in its advancing or latching direction of rotation by a spring-pressed camming device, generally indicated at 24, which also constitutes a holding means resisting reverse or anti-latching rotation of the bolt independently of the lock plate. The assembly of parts going to make up the camming device 24 will be referred to as holding means. The identities and relationship of these individual parts will be more clearly understood by reference to the perspective views in Figs. 5 through 9.

The bolt is engaged and urged in a latching direction by a wedge or cam element 25 having a slot 26 and an angular surface 27 which is brought into wedging engagement with one of the bolt heads 18a. One top corner of the cam element is notched and beveled at 28 and 29 to accommodate swinging movement of the outside handle operated on 30, see Fig. 2, as will later appear.

The latch mechanism optionally may include a bolt holding or dogging element in the form of a step plate 30, see Fig. 6, associated with and overlying the cam element 25. The step plate has a slot 31 registerable with slot 26 in the cam element, and is shaped to provide a series of stepped surfaces 32 in angular or inclined sequence, each surface being substantially parallel with the opposite straight side 33 of the plate and the inside surface 11b of the case flange along which the cam element and step plate are reciprocally slideable. The step plate carries a rearwardly projecting lug 34 and an arm 35 engageable, as will appear, by the releasing plate lug 36.

Referring now to Fig. 7, the releasing plate 37 there shown has an arm 38 having rearwardly turned end 39 which, together with the step plate lug 34, projects through a slot 40 in the case 10, as appearing in Fig. 2. A bottom corner of the plate 37 is notched at 41 to accommodate the inner end 42 of the inside operator arm 43, see Figs. 1 and 4, and the releasing plate is slotted at 44 to pass the key-controlled arm 45 which operates the lock plate 46.

In their assembled condition in the latch mechanism, the cam element, step plate and releasing plate occupy the position shown in Fig. 9. Normally the cam element 25 and step

plate 30 are held against relative longitudinal movement by a coil spring 47 contained within the slots 26 and 31 and confined between a pair of L-shaped pieces 48, see Fig. 3, overlapping the parts 25 and 30 so that longitudinal movement of either part tends, through the spring 47, to move the other part in the same direction. Upon upward movement of the releasing plate 37, the engagement of lug 36 with the step plate arm 35 produces corresponding lifting of the cam element and step plate assembly.

The locking plate 46 shown in Fig. 8 comprises an outwardly offset portion 46a joined along the bend 49 with an inwardly offset portion 46b which carries a flange 50 slideable on the bottom surface of the case 10. The outwardly offset portion 46a is shaped to overlie the assembly shown in Fig. 9 and to permit vertical displacement of the locking plate in its movements into and out of locking relation to the bolt. Plate 46 contains a slot 51 which receives the inner end of the key-controlled arm 45. The plate is notched at 52 to accommodate swinging movement of the inner end 42 of arm 43 in its actuations of the releasing plate, as will appear. The end 42 is engageable with a shoulder 53 integral with the locking plate and re-enforced by bracket 54, to move the locking plate from its retracted position of Fig. 1 to the bolt locking position of Fig. 3. Shoulder 55 is engageable by the arm to return the locking plate to normal retracted position. Plate 46 is releasably held in its two described positions by suitable detent, generally indicated at 56, see Fig. 4, shown typically as a spring arm 57 carrying a protuberance 58 engageable within either of openings 59 and 60 in the locking plate.

Referring now to Fig. 2, the cam element, step plate and releasing plate assembly of Fig. 9 is yieldably pressed toward the bolt to bring the wedge and stepped surfaces 27 and 32 in engagement therewith, by an arm 60 oscillating on a pivot 61 supported by spaced plates 62 and 63 integral with the case 10. The arm 60 is biased against arm 39 by a relatively strong coil spring 64 suitably supported at 65, to cause the releasing plate shoulder 38a to press against the upper end 25a of the cam. Arm 60 thus is operable to move the cam element, step plate and releasing plate from the retracted position of Fig. 3, to the bolt-engaging positions of Fig. 1 in which the step plate is urged against the bolt by the relatively weak spring 47 by reason of the cam movement to a position somewhat ahead of the step plate. An arm 30a carried by shaft 66 of the outside door handle (not shown) is movable by counter-clockwise rotation to engage lug 34 and lift the step plate, also the cam by way of spring 47, and the releasing plate 60 by the engagement of the cam end 25a with the releasing plate shoulder 38a, to their retracted positions. Normally the arm 30a is biased against lifting engagement with the lug 34, by a coil spring 67 connected to the arm hub 30a and a suitable support 68.

The lock plate 46 is shiftable between the positions of Figs. 1 and 3 by arm 45 pivotally mounted at 68 on a stationary support 69 integral with the case 10. The arm 45 is actuated 70 when engaged by a rotatable lug 70 carried on a key-operated or controlled shaft 71. It will be understood without necessity for specific illustration, that the shaft 71 will have associated therewith the conventionally used key plug, all in a manner such that turning of the key in a lock-

ing direction rotates shaft 71 and lug 70 in a clockwise direction, and reversely during unlocking turning of the key. The shaft and lug 70 are received within a cam surface slot 72 in the enlarged portion 45a of the arm 45. Assuming the locking plate to be in its retracted position of Fig. 2, clockwise rotation of shaft 71 brings lug 70 into engagement with surface 73 to swing the arm 45 downward to bolt locking position by the camming action of lug 70 against surface 73. The lug then is received within the enlarged diameter portion 74 of the slot 5. Arm 45 and the locking plate 46 are returnable to their unlocking positions by key controlled turning of lug 70 against surface 72 to cam the arm 45 upward to the normal unlocked position of Fig. 2.

Referring now to Fig. 4, the lever 43 is pivotally mounted at 76 on a suitable support 77 integral with the case 10 and is operable in the usual manner by an inside door handle (not shown) connected at 78 with the arm 79. Downward swinging movement of the lever 43 causes its end 42 to engage the lock plate shoulder 53 which shifts the plate to the bolt locking position of Fig. 3. Reverse swinging of the lever engages the end 42 with the locking plate shoulder 55 to restore the plate to its normal retracted position. Upward swinging of lever 43 from the normal or neutral position of Fig. 4 engages the end 42 with the releasing plate shoulder 80 to elevate the assembly of Fig. 9 and retract the cam element and step plate from holding engagement with the rotary bolt.

Considering now the operation of the described mechanisms, assume first the latch to be in opened condition, i. e. with the bolt entirely disengaged from the keeper, and with the cam thrust downwardly by the arm 60 to the limiting position permitted by the bolt. Upon bodily closing movement of the bolt, one of the bolt heads 18a engages the end surface 17a of the keeper and upon continuance of such movement the bolt is rotated to bring an adjacent head into engagement with the lower end of the cam and step plate assembly, displacing the latter upwardly against the resistance of the spring pressed arm 60 until the trip position of the cam is reached. This is the initial position at which the inclined cam surface 27 engages the bolt head to exert a thrust acting to cam and advance the bolt along the keeper in a direction of clockwise rotation to the home or fully latched position as in Fig. 1. At that position, reverse or anti-latching rotation of the bolt is resisted, and ordinarily effectively prevented, by the holding action of the cam surface against the bolt. When used, the step plate 30 serves as positive assurance against anti-latching bolt rotation in that should for any reason the cam become upwardly displaced, and therefore permit reverse rotation of the bolt, the bolt head engages one of the stepped surfaces 32 which, by reason of its parallel relation to the supporting surface 11b, presents until manually retracted, a positive barrier to further reverse bolt rotation.

A particular feature of improvement is a keeper-engaged abutment which serves to obviate looseness in the bolt position or condition resulting say from the capacity of the door for further closing movement after the bolt has reached a limiting home position under the influence of the cam. The abutment is shown to comprise a member or block 81 supported by or integral with a portion of the case, such as flange 82, which is engaged by the end portion

17a of the keeper preferably before the bolt reaches the ultimate home or latched position of which it is capable of reaching. Accordingly, the bolt thrust against the keeper serves constantly to maintain the abutment 81 in tight or snug engagement with the end of the keeper, thereby maintaining the parts in an engaged condition resistant to the development of looseness and vibration. The abutment 81 desirably may be given yielding characteristics, as by making it of rubber, so that it will remain in a state of compression while engaged with the keeper in a latched position of the bolt.

From the foregoing description it will be understood that the cam and step plate assembly may be retracted to release the bolt for opening or anti-latching rotation, either by operation of the outside handle shaft 68 and arm 30a independently of the releasing plate 31, or by actuation of the inside operated lever 43 and elevation of the assembly in Fig. 9. In either instance upon release of the retracting force, the cam is restored to engagement with the bolt by the action of arm 60 against arm 89.

Assume now that it is desired to lock the bolt in latched position, independently of the cam and step plate. By rotation of the key controlled shaft 71 as explained, arm 45 releases the locking plate 46 from the detent 58 and throws the locking plate down to the position of Fig. 3 in which the lower dog or projection 83 is brought into the path of reverse rotation of the bolt to lock the bolt against disengagement from the keeper. The plate 46 also is movable to bring the dog 83 into locking association of the bolt, by downward swinging of lever 43 from the inside door handle, and independently of the key-controlled operator. The plate 46 of course is retractable from its locked position by either the key controlled operator 45 or the inside handle controlled operator 43. It will be observed that retention of plate 46 in the bolt locking position, is independent of the cam and step plate position and any release thereof by the inside or outside handle-controlled operators.

Assume now the door to be in open position with the rotary bolt disengaged from the keeper with the cam thrust down against the side of the bolt, and assume also the latch to be in locked condition, i. e. with plate 46 in the position of Fig. 3. The dog 83 is automatically releasable from locking relation to the bolt as an incident of closing movement of the door, and specifically by virtue of advancing rotation of the bolt following its initial engagement with the end 17a of the keeper. The resulting bolt rotation causes the bolt to engage the lower end 83a of the locking dog, and to elevate the plate 46 to its retracted position.

The variational form of the invention shown in Figs. 10 to 18 is similar to the above described embodiment with respect to the general structure and arrangement of the case, bolt, keeper, the key-controlled operator and the inside and outside handle-controlled operators, and accordingly corresponding parts in the two embodiments are given corresponding reference numerals. The variational form differs primarily with respect to the structure and assembly of the cam and locking plates, the locking plate control and by incorporation of the bolt take-up feature mentioned in the introduction.

Here the cam plate 85 having an inclined wedge surface 86 is notched at 87 to form a shoulder 88 engageable by the outside handle-controlled

arm 301, see Fig. 10, to retract the cam. Plate 85 has a transverse extension 88 carrying a depending arm 90 and a lug 91 engageable by the inside handle-controlled lever 43 to elevate and retract the cam.

Associated with the cam plate is a locking plate 92 having the same general shape characteristics as the locking plate 46 in the first described form. The plate is slotted at 93 to contain a coil spring 94 bearing at its upper end against an inwardly projecting lug 95 on the plate. Slot 96 receives the key-controlled operator 45, as before. The side of the plate is notched at 97 to receive and accommodate upward swinging of the lever end 42 in its cam releasing movement. Between the detent receiving openings 98 and 99 the surface of the plate is raised to a mid-ridge 100 to form a cam tending to cause the locking plate to be moved under the influence of spring 97 fully to the detent setting positions in either direction of the plate travel. At its upper corner, the plate carries a rearwardly projecting arm 101 which has a pivotal connection 102 with an operator 103 controlled by push button 104 at the inside of the door 105. Directly associated and movable with the locking plate 92 is a take-up element 106 having a head 107 provided with a wedge surface 108 and a forwardly projecting lug 109. As illustrated in Fig. 10, the upper reduced width portion 110 of the element is adapted to extend at the left side of the spring 94. The lower end of the latter bears against lug 109 projecting forwardly through slot 93 in the locking plate so that the plate and element are movable together downwardly from the position of Fig. 10 to bring the wedge surface 108 into engagement with the bolt. Continued downward movement of the locking plate bringing the dog 111 into locking relation with the bolt 18, see Fig. 12, compresses the spring 94 to constantly thrust the element 106 against the bolt.

The manner of actuation and control of the cam plate 85 by arms 60 and 301 (the former engaging surface 112 of the cam plate) will be apparent from the foregoing description of the operation of the first illustrated form of the invention. Also it will be apparent that the cam plate likewise is retractable by upward swinging of the lever end 42 bearing against the lug 91. Moreover, it will be understood that, as before, advancing rotation of the bolt following its initial engagement with the keeper as the door is closed, serves to displace either or both the cam plate and the assembly of the locking plate 92 and take-up element 106 from bolt holding or locking positions to their retracted positions.

Plate 92 and the take-up element 106 are movable downwardly from the position of Fig. 10 to that of Fig. 12 by actuation of the key-controlled operator 45. The inside handle-controlled operator 43 however in this instance is ineffective to similarly throw the locking plate and take-up element assembly into bolt locking position since downward swinging of the lever end 42 below the position of Fig. 11 is limited by its engagement at 113 with the bottom of the case slot 114 through which the lever extends. However, the locking plate and take-up element are controllable at the inside of the door in both directions of their travel, by way of the push button operator 103.

When its wedge surface 108 is thrust against the bolt, the opposite straight edge of the take-up element bears and is supported against the flange 11 of the case. Thus a rigid resistance is imposed by the element against anti-latching

rotation of the bolt from any of its different latched positions. Whereas when using alone the simple form of dog 83 in the first described form, retraction of the cam 25 may permit some looseness in the dog and bolt engagement and limited capacity of the bolt for reverse rotation, the presence and action of the element 106 imposes a barrier which is self-acting to take up any bolt looseness or freedom of movement that might otherwise be permitted. Consequently, despite retraction of the cam, the parts cannot be shaken or vibrated in any manner to cause breakage or looseness permitting opening of the latch.

15 I claim:

1. A latch mechanism comprising a bolt rotatable in advancing and reversing directions and co-operable with a keeper to releasably secure a door to a stationary member, holding means

20 operable to rotatably advance said bolt in latched association with the keeper and movable to a position preventing rotation of the bolt in a reverse or anti-latching direction, an operator for retracting said holding means to release the bolt from latching association and engagement with the keeper, and a locking member normally retracted out of the path of reverse rotation of the bolt and movable into said path to lock the bolt against reversing rotation independently of said holding means, said locking member being movable to bolt releasing position by advancing rotation of the bolt resulting from its engagement with the keeper as the door is moved from open to closed positions.

25 2. A latch mechanism comprising a bolt rotatable in advancing and reversing directions and co-operable with a keeper to releasably secure a door to a stationary member, holding means

30 operable to rotatably advance said bolt in latched association with the keeper and movable to a position preventing rotation of the bolt in a reverse or anti-latching direction, an operator for retracting said holding means to release the bolt from latching association and engagement with the keeper, and a reciprocally displaceable locking member in side-by-side relation to said holding means, said locking member normally being retracted out of the path of reverse rotation of the bolt and being movable into said path to lock the bolt against reversing rotation independently of said holding means, said locking member being movable to bolt releasing position by advancing rotation of the bolt resulting from its engagement with the keeper as the door is moved from open to closed positions.

35 3. A latch mechanism comprising a bolt rotatable in advancing and reversing directions and co-operable with a keeper to releasably secure a door to a stationary member, holding means

40 operable to rotatably advance said bolt in latched association with the keeper and movable to a position preventing rotation of the bolt in a reverse or anti-latching direction, operators

45 controllable at the inside and outside of said door and individually actuatable to retract said holding means to release the bolt from latching association and engagement with the keeper, and a normally retracted locking member movable into the path of reverse rotation of the bolt to lock the bolt against reversing rotation independently of said holding means, said locking member being movable to bolt releasing position by said inside operator and also by advancing rotation of the bolt resulting from its engagement with the

keeper as the door is moved from open to closed positions.

4. A latch mechanism comprising a bolt rotatable in advancing and reversing directions and co-operable with a keeper to releasably secure a door to a stationary member, holding means operable to rotatably advance said bolt in latched association with the keeper and movable to a position preventing rotation of the bolt in a reverse or anti-latching direction, operators controllable at the inside and outside of said door and individually actuatable to retract said holding means to release the bolt from latching association and engagement with the keeper, and a normally retracted locking member movable by the inside operator into the path of reverse rotation of the bolt to lock the bolt against reversing rotation independently of said holding means, said locking member being movable to bolt releasing position by said inside operator and also by advancing rotation of the bolt resulting from its engagement with the keeper as the door is moved from open to closed positions.

5. A latch mechanism comprising a bolt rotatable in advancing and reversing directions and co-operable with a keeper to releasably secure a door to a stationary member, holding means operable to rotatably advance said bolt in latched association with the keeper and movable to a position preventing rotation of the bolt in a reverse or anti-latching direction, an operator for retracting said holding means to release the bolt from latching association and engagement with the keeper, a normally retracted locking member movable into the path of reverse rotation of the bolt to lock the bolt against reversing rotation independently of said holding means, said locking member being movable to bolt releasing position by advancing rotation of the bolt resulting from its engagement with the keeper as the door is moved from open to closed positions, and detent means for holding said locking member in its bolt releasing position.

6. A latch mechanism comprising a bolt rotatable in advancing and reversing directions and co-operable with a keeper to releasably secure a door to a stationary member, holding means operable to rotatably advance said bolt in latched association with the keeper and movable to a position preventing rotation of the bolt in a reverse or anti-latching direction, an operator for retracting said holding means to release the bolt from latching association and engagement with the keeper, a key-controlled operator, a normally retracted locking member movable by said key-controlled operator into the path of reverse rotation of the bolt to lock the bolt against reversing rotation independently of said holding means, said locking member being movable to bolt releasing position by advancing rotation of the bolt resulting from its engagement with the keeper as the door is moved from open to closed positions.

7. A latch mechanism comprising a bolt rotatable in advancing and reversing directions and co-operable with a keeper to releasably secure a door to a stationary member, holding means operable to rotatably advance said bolt in latched association with the keeper and movable to a position preventing rotation of the bolt in a reverse or anti-latching direction, an operator at the outside of the door for retracting said holding means to release the bolt from latching association and engagement with the keeper, a key-controlled operator, a normally

retracted locking member movable by said key-controlled operator into the path of reverse rotation of the bolt to lock the bolt against reversing rotation independently of said holding means, said locking member being movable to bolt releasing position by advancing rotation of the bolt resulting from its engagement with the keeper as the door is moved from open to closed positions, and an operator controllable at the inside of the door and actuatable to retract said holding means and also to move said locking member into and out of bolt locking position.

8. In a latch for association between two relatively movable parts, a bolt carried by one part, said bolt having a first position in which it cooperates with an associated keeper to restrain said parts in closed position and being movable from such position so as to enable it to clear said keeper and permit an opening movement of such parts, a holding member movably carried by said one part and operatively associated with said bolt in such relation as to enable it to prevent a said movement of said bolt, an operator actuatable to retract said holding member out of cooperative relation to said bolt so as to enable a said movement of said bolt, locking means which normally occupies a retracted position out of cooperative relation to said bolt but is movable from such retracted position into a locking position in which it blocks a said movement of said bolt despite the movement of the holding member out of cooperative relation to the bolt caused by an actuation of the operator, and means operated as an incident to a closing movement of said parts for restoring said locking means to the unlocked position.

9. In a latch for association between two relatively movable parts, a bolt carried by one part, said bolt having a first position in which it cooperates with an associated keeper to restrain said parts in closed position and being movable from such position so as to enable it to clear said keeper and permit an opening movement of such parts, a holding member movably carried by said one part and operatively associated with said bolt in such relation as to enable it to prevent a said movement of said bolt, an operator actuatable to retract said holding member out of cooperative relation to said bolt so as to enable a said movement of said bolt, locking means which normally occupies a retracted position out of cooperative relation to said bolt but is movable from such retracted position into a locking position in which it blocks a said movement of said bolt despite the movement of the holding member out of cooperative relation to the bolt caused by an actuation of the operator, said bolt being movable by said keeper in a direction which is the opposite of said first mentioned bolt movement during a closing movement of said parts, and being effective during said last mentioned opposite direction of movement to restore said locking means to said retracted position thereof.

10. In a latch for association between two relatively movable parts, a bolt carried by one part, said bolt having a first position in which it cooperates with an associated keeper to restrain said parts in closed position and being movable from such position so as to enable it to clear said keeper and permit an opening movement of such parts, a holding member movably carried by said one part and operatively associated with said bolt in such relation as to enable it to prevent a said movement of said

bolt, an operator actuatable to retract said holding member out of cooperative relation to said bolt so as to enable a said movement of said bolt, locking means which normally occupies a retracted position out of cooperative relation to said bolt but is movable from such retracted position into a locking position in which it blocks a said movement of said bolt despite the movement of the holding member out of cooperative relation to the bolt caused by an actuation of the operator, a key-controlled operator for moving said locking means from its said retracted position to said locking position, and means operated as an incident to a closing movement of said parts for restoring said locking means to the unlocked position.

11. In a latch for association between two relatively movable parts, a bolt carried by one part, said bolt having a first position in which it cooperates with an associated keeper to restrain said parts in closed position and being movable from such position so as to enable it to clear said keeper and permit an opening movement of such parts, a holding member movably carried by said one part and operatively associated with said bolt in such relation as to enable it to prevent a said movement of said bolt, an operator actuatable to retract said holding member out of cooperative relation to said bolt so as to enable a said movement of said bolt, locking means which normally occupies a retracted position out of cooperative relation to said bolt but is movable from such retracted position into a locking position in which it blocks a said movement of said bolt despite the movement of the holding member out of cooperative relation to the bolt caused by an actuation of the operator, a key-controlled operator for moving said locking means from its said retracted position to said locking position, said bolt being movable by said keeper in a direction which is the opposite of said first mentioned bolt movement during a closing movement of said parts, and being effective during said last mentioned opposite direction of movement to restore said locking means to said retracted position thereof.

12. A latch mechanism comprising a bolt rotatable in advancing and reversing directions and co-operable with a keeper to releasably secure a door to a stationary member, holding means operable to rotatably advance said bolt in latched association with the keeper and positioned to prevent rotation of the bolt in a reverse or anti-latching direction, a first operator controllable at the inside of the door for retracting said holding means to release the bolt from latching association and engagement with the keeper, a second operator controllable at the inside of the door independently of said first operator, a normally retracted locking member movable into the path of reverse rotation of the bolt to lock the bolt against reversing rotation independently of said holding means, said locking member being movable to bolt releasing position by said second operator and by advancing rotation of the bolt resulting from its engagement with the keeper as the door is moved from open to closed positions.

13. A latch mechanism comprising a bolt rotatable in advancing and reversing directions and co-operable with a keeper to releasably secure a door to a stationary member, holding means operable to rotatably advance said bolt in latched association with the keeper and positioned to

prevent rotation of the bolt in a reverse or anti-latching direction, a normally retracted locking member movable into the path of reverse rotation of the bolt to lock the bolt against reversing rotation independently of said holding means, a first operator controllable at the inside of the door for retracting said holding means to release the bolt from latching association and engagement with the keeper, said first operator being inoperative to retract said locking member from bolt locking position, a second operator controllable at the inside of the door independently of said first operator, said locking member being movable to bolt releasing position by said second operator and by advancing rotation of the bolt resulting from its engagement with the keeper as the door is moved from open to closed positions.

14. A latch mechanism comprising a bolt rotatable in advancing and reversing directions and co-operable with a keeper to releasably secure a door to a stationary member, holding means operable to rotatably advance said bolt in latched association with the keeper and positioned to prevent rotation of the bolt in a reverse or anti-latching direction, a first operator controllable at the inside of the door for retracting said holding means to release the bolt from latching association and engagement with the keeper, a second operator controllable at the inside of the door independently of said first operator, a key-controlled operator, a normally retracted locking member movable by said key-controlled operator into the path of reverse rotation of the bolt to lock the bolt against reversing rotation independently of said holding means, said locking member being movable to bolt releasing position by said second operator and by advancing rotation of the bolt resulting from its engagement with the keeper as the door is moved from open to closed positions.

15. A latch mechanism comprising a bolt rotatable in advancing and reversing directions and co-operable with a keeper to releasably secure a door to a stationary member, holding means operable to rotatably advance said bolt in latched association with the keeper and positioned to prevent rotation of the bolt in a reverse or anti-latching direction, an operator for retracting said holding means to release the bolt from latching association and engagement with the keeper, locking means actuatable to lock the bolt against reverse rotation independently of said holding means, said locking means normally being out of the path of reverse rotation of the bolt and therefore being ineffective to so lock the bolt against reverse rotation, and a key-controlled operator for actuating said locking means to lock the bolt, said locking means being releasable by advancing rotation of the bolt during movement of the door from open to closed positions.

16. A latch mechanism comprising a bolt rotatable in advancing and reversing directions and co-operable with a keeper to releasably secure a door to a stationary member, holding means operable to rotatably advance said bolt in latched association with the keeper and positioned to prevent rotation of the bolt in a reverse or anti-latching direction, a first operator controllable at the outside of the door for retracting said holding means to release the bolt from latching association and engagement with the keeper, locking means actuatable to lock the bolt against reverse rotation independently of said holding means, said locking means normally being inef-

fective to so lock the bolt against reverse rotation, a second operator controllable at the inside of the door independently of said first operator to actuate said locking means, and a key-controlled operator for actuating said locking means to lock the bolt, said locking means being releasable by advancing rotation of the bolt during movement of the door from open to closed positions.

17. In a latch mechanism, a bolt rotatable in advancing and reversing directions and co-operable with a keeper to releasably secure a door to a stationary member, actuating means for advancing the bolt through progressive positions of latched engagement with the keeper and for holding the bolt against reverse or anti-latching rotation, said actuating means being retractable to permit said reverse rotation of the bolt, and means operable when said actuating means is retracted to hold the bolt against reverse rotation from any of said progressive latched positions.

18. In a latch mechanism, a bolt rotatable in advancing and reversing directions and co-operable with a keeper to releasably secure a door to a stationary member, actuating means for advancing the bolt through progressive positions of latched engagement with the keeper and for holding the bolt against reverse or anti-latching rotation, said actuating means being retractable to permit said reverse rotation of the bolt, and means constantly engageable with the bolt in said progressive latched positions thereof when said actuating means is retracted to hold the bolt against reverse rotation from any of said positions.

19. In a latch mechanism, a bolt rotatable in advancing and reversing directions and co-operable with a keeper to releasably secure a door to a stationary member, actuating means for advancing the bolt through progressive positions of latched engagement with the keeper and for holding the bolt against reverse or anti-latching rotation, said actuating means being retractable to permit said reverse rotation of the bolt, and means independent of said actuating means and movable into the path of reverse rotation of the bolt to lock the bolt against reverse rotation and engageable with the bolt in said progressive latched positions to prevent reverse rotation of the bolt from any of those positions.

20. In a latch mechanism, a bolt rotatable in advancing and reversing directions and co-operable with a keeper to releasably secure a door to a stationary member, actuating means for advancing the bolt through progressive positions of latched engagement with the keeper and for holding the bolt against reverse or anti-latching rotation, said actuating means being retractable to permit said reverse rotation of the bolt, and means including a spring-pressed element operable when said actuating means is retracted to hold the bolt against reverse rotation from any of said progressive latched positions.

21. A latch mechanism comprising a bolt rotatable in advancing and reversing directions and co-operable with a keeper to releasably secure a door to a stationary member, holding means operable to rotatably advance said bolt through progressive positions of latched association with the keeper and positioned to prevent rotation of

the bolt in a reverse or anti-latching direction, an operator for retracting said holding means to release the bolt from latching association and engagement with the keeper, and a normally retracted locking means movable into the path of reverse rotation of the bolt to lock the bolt against reversing rotation independently of said holding means, said locking means being movable to bolt releasing position by advancing rotation of the bolt resulting from its engagement with the keeper as the door is moved from open to closed positions, and said locking means being operable when said holding means is retracted to hold the bolt against reverse rotation from any of said progressive latched positions.

22. A latch mechanism comprising a bolt rotatable in advancing and reversing directions and co-operable with a keeper to releasably secure a door to a stationary member, holding means operable to rotatably advance said bolt through progressive positions of latched association with the keeper and positioned to prevent rotation of the bolt in a reverse or anti-latching direction, an operator for retracting said holding means to release the bolt from latching association and engagement with the keeper, and a normally retracted locking means movable into the path of reverse rotation of the bolt to lock the bolt against reversing rotation independently of said holding means, said locking means being movable to bolt releasing position by advancing rotation of the bolt resulting from its engagement with the keeper as the door is moved from open to closed positions, and said locking means being constantly engageable with the bolt in said progressive positions thereof when said holding means is retracted to hold the bolt against reverse rotation from any of said positions.

23. A latch mechanism comprising a bolt rotatable in advancing and reversing directions and co-operable with a keeper to releasably secure a door to a stationary member, holding means operable to rotatably advance said bolt in latched association with the keeper and positioned to prevent rotation of the bolt in a reverse or anti-latching direction, a normally retracted locking means movable into the path of reverse rotation of the bolt to lock the bolt against reversing rotation independently of said holding means, and individually controllable operators selectively actuatable at the inside or outside of the door to move said locking means into and out of locking association with the bolt.

24. A latch mechanism comprising a bolt rotatable in advancing and reversing directions and co-operable with a keeper to releasably secure a door to a stationary member, holding means operable to rotatably advance said bolt in latched association with the keeper and positioned to prevent rotation of the bolt in a reverse or anti-latching direction, a normally retracted locking means movable into the path of reverse rotation of the bolt to lock the bolt against reversing rotation independently of said holding means, a key-controlled operator actuatable at the outside of the door, and a second operator actuatable at the inside of the door, said operators being selectively actuatable to move said locking means into and out of locking association with the bolt.
